UNITED STATES PATENT OFFICE.

ROBERT F. LONABERGER AND CHARLES F. SANDS, OF READING, PENNSYLVANIA, AS
SIGNORS TO LLOYD A. UNGER, TRUSTEE.

LIQUID-FUEL VAPORIZER FOR INTERNAL-COMBUSTION ENGINES.

Application filed April 13, 1922. Serial No. 552,414.

To all whom it may concern:

Be it known that we, ROBERT F. LONABERGER and CHARLES F. SANDS, citizens of the United States, residing at Reading, 5 county of Berks, State of Pennsylvania, have invented an Improvement in Liquid-Fuel Vaporizers for Internal-Combustion Engines, of which the following description, in connection with the accompanying drawings, is a specification, like characters on the drawings representing like parts.

In engines constructed to use gasoline, not only is the expense of operation high because of the scarcity of gasoline, but it is 15 found that under certain conditions of operation an undesirable knocking and loss of power occurs in the cylinders, thought to be due to imperfect carburetion. This invention aims to adapt an ordinary four stroke 20 cycle internal combustion engine, constructed to operate on gasoline or other readily vaporized fuel, for operating on a heavy fuel such as kerosene, distillate or fuel oil. The invention further aims to improve the 25 operation of internal combustion engines and increase their thermal efficiency.

Further aims and advantages of the invention appear in connection with the following description of a preferred form of 30 the invention illustrated in the drawings.

Referring to the drawings, Fig. 1 is a side elevation of an internal combustion engine showing the invention applied thereto in a preferred form;

35 Figure 2 is an end elevation of the same, partly in section on the line 2—2 in Fig. 1, looking in the direction of the arrows;

Figure 3 is an enlarged transverse sectional view of the electric heating element 40 and vaporizer, showing the adjacent portion of the engine in elevation, the section being taken on the line 3—3 in Fig. 1, looking in the direction of the arrows;

Figure 4 is a longitudinal sectional view 45 of the same taken on the line 4—4 in Fig. 3, showing the means for operating the fuel admission valve; and

Figure 5 is a horizontal sectional view 50 of the cam and control device for the fuel valve operating means, taken on the line 5—5 in Fig. 4, looking up.

The engine shown in the drawings (See 55 Figs. 1 and 2) is of the conventional four cylinder type having an explosion in one of the four cylinders upon each stroke. As

shown in the drawings, the cylinders are L type formed in a cylinder block 11 and provided with inlet and exhaust valves 12 of usual construction actuated by cams and tappet rods or other suitable means operated from a half time shaft 13 that is driven 60 from the crank shaft 14 by gearing having a 1 to 2 ratio of teeth. The cylinder block 11 is also provided with inlet passages 15 having a connection 16 for a carburetor and exhaust passages leading to the exhaust manifold 17. The pistons 18 and connecting rods 19 may be of any suitable type, connected to the crank shaft to rotate it in the usual manner.

70 Any satisfactory system of ignition may be utilized such as a jump spark, for which spark plugs 20 are mounted in the separable head 21, one projecting into the head space of each cylinder, and are connected by wires 75 to a suitable magneto or sparking device (not shown). The type, arrangement and detail construction of the engine and its operating parts heretofore mentioned are shown and described only by way of illustration and the invention is not restricted thereto.

80 The cylinders, head and valves are water-jacketed, circulation of water being maintained by a pump or other suitable means, 85 not shown, through the water jackets 22 and manifold 23 to a radiator or other cooling device, the water first passing around the fuel vaporizer 24 and entering the cylinder block by means of the branch pipes 25. (See 90 Figs. 1, 2 and 3). This arrangement assists in maintaining the vaporizer and fuel passages to the cylinders at a uniform temperature conducive to smooth and efficient operation.

95 The vaporizer 24 is secured to the carburetor connection 16 in place of a carburetor of any usual type. The vaporizer has an electric heating element 26 (see Fig. 3) for vaporizing liquid fuel, and a mixing tube 100 27, where the vaporized fuel is mixed with air and conducted to the connection 16 leading to the inlet valves. A manually controlled valve 28 regulates the flow of air into the mixing tube.

105 Liquid fuel is supplied to the vaporizer through the pipe 29, at a constant pressure maintained by a suitable pump 30 and relief valve 31, and a mechanically actuated valve 32 (see Fig. 4) periodically opens to 110

permit a fresh charge of fuel to reach the vaporizer. The amount of opening of this valve 32 can be regulated manually by the control lever 33 to control the power output of the engine.

The valve 32 is normally held closed by a spring 34 contained in the valve housing and bearing against a cup shaped flange 35 on the stem of the valve. The valve is opened 10 to admit a charge of fuel to the vaporizer upon each stroke by means of a lever 36, having a yoke on one arm bearing against the flange 35 and a bearing on the other arm for engagement by a tappet rod 37 slidably 15 mounted in the cam housing 38. The valve, operating cams 39 are four in number, carried by a cam plate 40 slidably mounted on the cam shaft 41 to move toward and away from the tappet rod 37 to increase or decrease 20 the movement of the latter and thereby control the amount of opening of the fuel valve 32. The cam shaft 41 is rotated at the same speed as the half time shaft 13 by suitable gears 42, 43, as shown in Fig. 2. 25 The driving gear 43 is adjustably secured to the cam shaft 41 by means of a crown gear 44 having fine teeth engaging similar teeth on the gear 43 so that slight changes in the angular position of the shaft with respect to 30 the driving gear may be made to suit different engines to which the device may be applied.

The cam plate 40 is secured to a sleeve 45 splined on the cam shaft 41 and is normally 35 held in its position farthest from the operating rod 37 by means of a spring 46 enclosed by the sleeve and bearing against a flange 47 on the shaft, as shown in Figs. 4 and 5. The housing has a groove for engagement by 40 a yoke 48 on the control lever 33 whereby it may be held in position to cause the cams to open the fuel valve 32 the desired amount. Any suitable operating means (not shown) for the control lever 33 and valve 28 may be 45 used.

The fuel valve 32 may be provided with an adjustable stem 49 through which the valve extends and with which it has a threaded engagement at its outer end, where 50 it may be locked in adjusted position by a nut 50 or other suitable means. The valve stem is provided with rings 51 to prevent leakage of fuel past it. The valve stem and valve are mounted in a hardened steel bushing 52 that is forced into the vaporizer housing and secured by a set screw 53.

The vaporizer 24 comprises a casing 54 containing a porcelain or other suitable insulator 55 for the electrode 56, and is detachably secured in the vaporizer housing by a sleeve nut 57. The insulator 55 is formed with a central passage 58 communicating with the vapor discharge passage 59, and the inner end of this passage 58 is surrounded by an annular passage into which

liquid fuel is injected when the fuel valve 32 opens. The heating element 60 is contained in a thimble 61 molded in the insulating material and extending through the passage 58.

Reference is made to our pending application filed August 15, 1921, Serial No. 492,398, for a further description of the electric heating and vaporizing unit and its operation.

The waterjacketed fuel vaporizer, fuel pump, mixing tube, air control valve, and fuel control valve and its operating means, all are contained in a unitary assemblage, housed in suitable casings to protect them from dirt and enable them to be properly lubricated, and mounted on the bracket 62, whereby, with suitable modification, they may be attached to many of the usual types of internal combustion engines.

The fuel control valve is timed to admit fuel to the vaporizer after the inlet valve of the cylinder has opened, thereby causing a charge of non-carbureted air to enter the cylinder in advance of the admission thereto of the explosive mixture formed in the mixing tube when fuel is admitted to the vaporizer. The delay in the opening of the fuel control valve is slightly greater for the minimum valve opening than for the maximum valve opening, thereby diminishing the liability of the lean mixture formed when the engine is running on a closed throttle to back fire.

The operation of the engine is similar to that of ordinary four stroke cycle internal combustion engines provided with the usual types of carburetors or liquid fuel vaporizers except that the time of injection of the fuel into the air entering the cylinders on the suction stroke is later than in ordinary engines and is varied slightly with the amount of opening of the fuel valve 32. The electric vaporizer furnishes a suitable vaporized fuel to start the engine cold. Hence a heavy fuel is utilized without requiring any primer or other starting attachment.

A very smooth running engine results from this method of operation because the fuel is completely vaporized before it enters the cylinders, the amount of fuel and the time of admitting fuel vapor to the cylinders may be controlled with precision and according to the amount of fuel required under varying conditions, and a partial charge of air is admitted to the cylinders prior to fuel vapor on the suction stroke, thereby reducing carbon deposit and preventing pre-ignition.

The invention is not restricted to the details of construction illustrated in the drawings, as manifestly it may be adapted to various types of engines.

We claim the following as our invention:

1. An attachment for internal combustion

engines comprising a waterjacketed fuel vaporizer and mixing tube having an air control valve, a fuel pump and fuel control valve, and operating means for intermittently actuating said fuel control valve in synchronism with the inlet and exhaust valves of said engine.

2. An attachment for internal combustion engines comprising a waterjacketed fuel vaporizer and mixing tube having an air control valve, a fuel pump and fuel control valve, means for varying the amount of opening of said fuel control valve, and operating means for intermittently actuating said fuel control valve in synchronism with the inlet and exhaust valves of said engine.

3. An attachment for internal combustion engines comprising a waterjacketed fuel vaporizer and mixing tube having an air control valve, a fuel pump and fuel control valve, operating means for intermittently actuating said fuel control valve in synchronism with the inlet and exhaust valves of said engine, and means for delaying the time of opening said fuel control valve when less than a full charge of fuel is admitted to said vaporizer.

4. An attachment for internal combustion engines comprising a waterjacketed fuel vaporizer and mixing tube having an air control valve, a fuel pump and fuel control valve, and operating means for intermittently actuating said fuel control valve in synchronism with the inlet and exhaust valves of said engine, said operating means consisting of a tappet and a rotating cam plate having axial movement to engage said tappet to move it a greater or less amount as desired.

5. An attachment for internal combustion engines comprising a waterjacketed fuel vaporizer and mixing tube having an air control valve, a fuel pump and fuel control valve, operating means for intermittently actuating said fuel control valve in synchronism with the inlet and exhaust valves of said engine, and means for delaying the time of opening said fuel control valve when less than a full charge of fuel is admitted to said vaporizer, said means consisting of a tappet rod and rotating cam plate having cams adapted to engage said tappet with a greater or less portion of their contour depending upon the amount of opening of said valve desired.

55 6. An attachment for internal combustion engines of the type in which a combustible mixture is drawn into the cylinder on the suction stroke, said attachment comprising a housing adapted to be attached to the fuel inlet passage of said engine, a fuel vaporizer and mixing tube carried by said housing, an air inlet into said mixing tube and control valve therefor, and a fuel inlet to said vaporizer, said fuel inlet having a valve normally closed, and said housing having a cam shaft

and means for opening said valve periodically, and connections to said engine for rotating said shaft.

7. In an internal combustion engine having cylinders provided with inlet and exhaust valves and means for operating them, electric means for vaporizing fuel outside said cylinders, means actuated by said engine for admitting fuel to said vaporizing means periodically in synchronism with the operation of said valves, and means for varying the time of admitting fuel to said vaporizer according to the amount of fuel admitted, whereby knocking in the cylinders is prevented.

8. A heavy fuel vaporizer for internal combustion engines comprising a housing containing a heating element, a fuel pipe leading to said heating element and a valve normally closing said pipe, a shaft mounted in said housing, means for rotating said shaft from the engine, a bushing slidable on said shaft, a cam on said bushing and means engaged thereby for operating said valve and means for positioning said bushing and cam lengthwise on said shaft for controlling the amount of opening of said valve.

9. A heavy fuel vaporizer for internal combustion engines comprising a housing containing a heating element, a fuel pipe leading to said heating element and a valve normally closing said pipe, a shaft mounted in said housing, means for rotating said shaft from the engine, a bushing slidable on said shaft, a cam on said bushing and means engaged thereby for operating said valve and means for positioning said bushing and cam lengthwise on said shaft for controlling the time and amount of opening of said valve.

10. A heavy fuel vaporizer for internal combustion engines comprising a housing containing a heating element, a waterjacket surrounding said heating element and water inlet and outlet pipes therefor, said outlet pipe having a discharge orifice adapted to be secured to the waterjacket of the engine, a fuel pipe leading to said heating element and a valve normally closing said pipe, a shaft mounted in said housing, means for rotating said shaft from the engine, a cam on said shaft and means engaged thereby for operating said valve, and means for positioning said cam on said shaft for controlling the amount of opening of said valve.

11. A heavy fuel carburetor for internal combustion engines comprising a fuel vaporizer in communication with the inlet passages thereof, electric heating means for said vaporizer, means operated by said engine for intermittently admitting fuel to said vaporizer, and manually controlled means for varying the time of admission of fuel to said vaporizer to suit the conditions of operation of said engine.

12. A heavy fuel carburetor for internal

combustion engines comprising a fuel vaporizer in communication with the inlet passages thereof, electric heating means for said vaporizer, means operated by said engine for intermittently admitting fuel to said vaporizer, means for admitting air to said carbureter in advance of the admission of fuel to said vaporizer, and means for varying the time of admission of fuel to said vaporizer to suit the conditions of operation of said engine.

13. A heavy fuel carbureter for internal combustion engines comprising a fuel vaporizer in communication with the inlet passages thereof, electric heating means for said vaporizer, means operated by said engine for intermittently admitting fuel to said vaporizer, means for admitting air to said carbureter in advance of the admission of fuel to said vaporizer, means for varying the time of admission of fuel to said vaporizer to suit the conditions of operation of said engine, and manually controlled means for varying the amounts of air and fuel admitted to said carbureter.

14. An attachment for internal combustion engines comprising a fuel vaporizer, a fuel pump and fuel control valve, and operating means for intermittently actuating said fuel control valve in synchronism with the inlet and exhaust valves of said engine, said operating means comprising a shaft having a driving gear loosely mounted thereon and a crown gear fixed to said shaft and having fine teeth adapted to be engaged with similar teeth on said driving gear,

whereby the angular relationship of said driving gear and shaft may be adjusted to suit the engine.

15. An attachment for internal combustion engines comprising a fuel vaporizer, a fuel pump and fuel control valve, and operating means for intermittently actuating said fuel control valve in synchronism with the inlet and exhaust valves of said engine, said operating means comprising means whereby the angular relationship of said driving gear and shaft may be adjusted to suit the engine.

16. An attachment for internal combustion engines comprising a waterjacketed fuel vaporizer and mixing tube having an air control valve, a fuel pump and fuel control valve, operating means for intermittently actuating said fuel control valve in synchronism with the inlet and exhaust valves of said engine, and means for delaying the time of opening said fuel control valve when less than a full charge of fuel is admitted to said vaporizer, whereby a heavy fuel may be utilized without knocking in the cylinder of said engine.

17. A heavy fuel vaporizing and mixing attachment for internal combustion engines having means for heating the fuel and for varying the amount and time of admission thereof to correspond to the conditions of operation, substantially as described.

In testimony whereof, we have signed our names to this specification.

ROBERT F. LONABERGER.
CHARLES F. SANDS.
